COMBINED SWITCH AND FASTENER

John W. Liley, Ferndale, Mich., assignor of fifty-five per cent to Michael J. Basso, Detroit, Mich.

Application May 22, 1951, Serial No. 227,640

27 Claims. (Cl. 200—54)

1

This invention relates to electrical switches, and more particularly to a combined switch and fastener construction especially adapted for use in combination with the hinges of vehicle and other doors. This application is a continuation-in-part of my applications Serial No. 121,624, filed October 15, 1949, and Serial No. 164,159, filed May 5, 1950.

In the past, switch constructions have been provided adapted to be actuated by the opening and closing of a closure means such as a door, for operating a lighting circuit or similar electrical circuit. In the conventional switch of this type, the switch unit must be mounted on the door frame by means of a separate opening in the frame, thus requiring the additional labor and expense of forming this opening, as well as the provision of fastener means for attaching the switch adjacent the opening.

It is an object of the present invention to overcome the disadvantages of the conventional door switch construction, and to provide a door operated switch which eliminates the necessity of forming an extra opening in the door frame, but which can be installed in the assembly simultaneously with the attaching of the door hinges to the frame, without any additional labor being required.

It is a further object to provide a switch of the above character, which is combined with a fastener used to attach the hinge to the door frame, so that the switch operates through the fastener opening, and requires no additional elements for securing the switch to the frame.

It is another object of the invention to provide an electrical switch of the above character, which is of the plunger type, and in which the plunger is disposed axially within one of the hinge fasteners, whereby the fastener serves the dual purpose of supporting the door hinge and guiding the movement of the switch plunger.

It is also an object of the invention to provide a switch of the above type, in which the fastener may be rotated into its fastening position without disturbing the wiring connection of the switch. In association with this object, it is within the contemplation of this invention to provide a switch wherein the wiring harness may be pulled through the door frame fastener opening and the hinge fastener opening, and then attached to the switch, the fastener thereafter being applied to the door frame in the usual manner, without disturbing this connection.

It is a further object, in several forms of my invention, to provide a switch of the above char-

acter, in which the fastener itself functions as one of the switch terminals, and in which the switch is capable of closing its contacts even though dirt or other foreign matter may be present on the terminals.

It is also an object, in another form of the invention, to provide a switch of the above type, which is especially adapted for two-wire circuits, and in which the fastener does not form part of the circuit.

It is a further object of the invention to provide a switch of the above character, which is of extremely efficient construction, and in which there are few moving parts to get out of order.

Other objects, features, and advantages of the present invention will become apparent from the subsequent description, taken in conjunction with the accompanying drawings.

In the drawings:

Figure 1 is a side view, partly in cross-section, of a preferred form of the combined switch and fastener, wherein the fastener is utilized as one of the terminals of the switch;

Figure 2 is a side view, partly in cross-section, of the switch shown in Figure 1 installed in a door frame and hinge, the switch being shown in its open position;

Figure 3 is a front view of the switch of Figures 1 and 2 showing the disposition of the plunger within the fastener;

Figure 4 is a side view, partly in cross-section, of a modified form of the improved switch, having the plunger spring enclosed within the unit;

Figure 5 is a fragmentary cross-sectional view of another modification of the switch, utilizing a plunger of nonconductive material;

Figure 6 is a side cross-sectional view of still another modification of the switch, for use with a two-wire circuit wherein two terminal sets are used;

Figure 7 is a cross-sectional view taken along the line 7—7 of Figure 6 and showing the guide means for the contacts;

Figure 8 is a fifth embodiment of the invention, similar in principle to that of Figure 6, but having a modified terminal construction; and

Figure 9 is a cross-sectional view taken along the line 9—9 of Figure 8 and showing the lateral configuration of the elements.

The invention is shown as applied to a fastener used for attaching a door hinge to the door frame, so that the switch is operated by the opening and closing of the door. It will be understood however, that the principles of the invention are equally applicable to other types of fas-

teners, where it is desired to have a switch operated by an element extending from one of the members secured by the fastener.

The invention comprises in general a fastener such as a screw or bolt which is of essentially standard construction, this fastener being combined with and forming a part of a plunger-type switch. The plunger is disposed axially within the fastener, the latter supporting the plunger for axial movement therein. Resilient means are provided for normally urging the plunger outwardly from the head of the fastener, this resilient means being yieldable to allow a fastening tool to be applied to the fastener when it is being assembled. The inner end of the plunger supports one or more switch terminals, these terminals being movable axially with the plunger, so that the switch is closed when the plunger extends from the fastener, and is open when the plunger is partially or fully depressed. In its simplest form, the invention contemplates the use of the inner end of the fastener as one of the switch terminals, although this need not be the case. The mounting of the plunger within the fastener, as well as the method of attaching the switch terminals to the inner end of the plunger, is such that the fastener may be rotated into its fastening position without turning the switch terminals or twisting the wires which are attached to such terminals. The method of attaching the terminal or terminals to the inner end of the plunger is preferably such that relative lateral movement or pivoting action is permitted between the terminals, thus insuring closure of the switch despite dirt or other foreign matter which may accumulate on the contacts.

Referring more particularly to the drawings, Figures 1-3 illustrate a preferred embodiment of the invention in which the fastener, generally indicated at 11, is shown as a Phillips head screw of the type used in attaching vehicle doors, refrigerator doors and the like to their respective door frames. The screw 11 has a shank portion 12 provided with an external thread 13, and a tapered head portion 14 having a socket 15 for receiving a Phillips head tool (not shown), and being adapted to engage a lock washer 16. The screw 11 is essentially of standard manufacture, but is preferably provided with a chamfered or tapered surface 17 at its inner end, and an axial bore 18. The bore 18 extends axially from the socket 15, the inner end of the bore being of smaller diameter and provided with a radial shoulder 19, so that the end of the shank has a bearing portion 21 for supporting and guiding the switch plunger 22.

Plunger 22 is essentially of rod-like or cylindrical shape, and supports the resilient spring 23 which is disposed around its periphery and is utilized to normally urge the plunger outwardly from the fastener head. Spring 23 engages at one end the shoulder 19 of the bore 18, and at its other end a head 24 which is formed at the outer end of the plunger 22. As is seen in Figure 1, the plunger may be of slightly tapered shape so that a small clearance space 25 exists between the plunger and the guide surface 21 when the plunger is extended. The material of which the plunger is made is not critical, although it is preferably fabricated of metallic stock or other material having substantial strength and durability.

The inner end of the plunger 22 supports a tubular member generally indicated at 26, of conductive material, this tubular member serv-

ing as both a switch terminal and as connecting means for the insulated wire conductor 27 which leads from the battery (not shown) or other source of electrical power. For this purpose, a supporting member generally indicated at 28 is provided for securing member 26 to the inner end of the plunger, this supporting member being preferably fabricated of a plastic or other non-conductive material such as nylon. The inner end of plunger 22 is provided with a reduced portion 29 having an annular gripping ring 31 integral therewith. The supporting member 28 is provided with a recess 32 extending axially therein, and the reduced portion 29 of the plunger is disposed within this recess, so that the supporting member 28 abuts the shoulder 33 between reduced portion 29 of the plunger and the main portion of this plunger. Since the gripping ring 31 preferably has a forced fit with the supporting member 28, the latter member is thus fixedly secured to the inner end of the plunger.

The supporting member is provided with an annular groove 34 which extends around its otherwise cylindrical surface, this groove having outwardly flared side walls 35. The tubular member 26 has a mounting and contact section 36 and a connector section 37 which is of somewhat smaller diameter than the section 36. When the switch is assembled, the section 36 is slipped axially over the supporting member 28 and is preferably secured thereto by pressing section 36 inwardly adjacent groove 34, so that a plurality of projections 38 are provided extending into this groove. It will be observed that a slight clearance space 39 is provided between the projections 38 and the bottom and side walls of groove 34. It will thus be seen that relative rotation between the tubular member 26 and the supporting member 28 is permitted, and in particular that the tubular member may be held from rotating, for instance by the attached wire 27, while the supporting member 28 rotates with the plunger and the fastener 11 while the fastener is being attached. It will be understood that other types of securing means could be provided between the tubular member 26 and the plunger 22 to allow relative rotation therebetween, without violating the principles of the invention.

When in its assembled position the tubular member 26 extends past the shoulder 33 so that it is free to engage the tapered surface 17 of the fastener 11. For this purpose, the tubular member is provided with a flared contact flange 41 engageable with an intermediate portion of this tapered surface. It will be observed that when flange 41 engages surface 17, a substantial axial distance exists between the end 42 of the fastener and the end surface 43 of supporting member 28. The contacts 17 and 41 are thus assured of positive engagement, since the compression in spring 23 will urge the plunger 22 constantly outwardly.

The bared end of conductor 27 is preferably attached to the connector section 37 of the tubular member by means of crimping section 37, as shown for example at 44. It will be understood however that other methods of attaching the conductor 27 to the tubular member could be used. It will be seen that when the conductor is secured to the tubular member, a continuous electrical path will exist from the conductor to the contact surface 41. It will also be noted that the conductor is completely insulated from the plunger 22 since the supporting member 28, which is of

non-conductive material, prevents any contact of these two elements. It is also important to observe that due to the play 39 which exists between the tubular member and the supporting member, it is possible for the contact surface 41 to engage a portion of the contact surface 17, while dirt or other foreign matter prevents engagement of other portions of these surfaces. This is because the tubular element is allowed a pivoting action around the supporting member 28 without disengaging projections 38 and groove 34.

The application of the combined switch and fastener to a door hinge is shown in Figure 2. In this illustration, one leaf 45 of the hinge is shown as being secured to the door frame 46, the fastener 11 being threadably engaged with an internally threaded member 47 such as a nut which is welded or otherwise secured to the inside of the frame. In assembling the switch and fastener in this manner, the wire 27 is first passed through the nut 47 and the openings in frame 46 and hinge leaf 45. The bare end of the wire 27 is then crimped within the section 37 of tubular member 26. The hinge and frame holes are then aligned, and the wire and tubular member pushed back through these holes. It will be observed that the tubular member will pass freely through the nut 47, since its diameter is substantially less than that of thread 13. The threads of the screw 11 are then engaged with nut 47, and the screw is driven to its full home position by means of a wrench or other tool.

It is a principle of the invention that the tool for driving the fastener may be applied without interference from the switch portion of the device, and without disturbing the switch portion in any way. The operation of this principle will be obvious from the foregoing discussion, since it will be seen that when the tool is applied to socket 15, it will depress plunger 22 by contact with its head 24, compressing spring 23, so that the plunger will be retracted within bore 18 of the fastener. This position is shown in dot-dash lines in Figure 2, and it will be seen from this figure and from Figure 3 that the plunger is capable of full retraction so that the tool may fully enter the socket 15. When this action occurs, the contacts 17 and 41 will of course be separated. As the fastener is rotatably driven, friction between the fastener and plunger, especially through the intermediary of the spring 23, will cause rotation of the plunger as well as of supporting member 28. Since, as described previously, definite play 39 exists between the supporting member 28 and tubular member 26, the tubular member will not be forced to rotate with the supporting member. This will prevent unwanted twisting of the wire 27 within the door frame. When the fastener has been driven fully home, removal of the tool will cause immediate projection of plunger 22, and the contacts 17 and 41 will thereafter be normally engaged. Since fastener 11 is grounded to the frame, a lighting or other circuit will be completed by the contact.

In operation, with the door (not shown) normally closed, the hinge leaf 48 attached to the door will engage the head 24 of the plunger, thus retracting the plunger and separating the contact surfaces 17 and 41 to open the electrical circuit. Upon opening of the door, the hinge leaf 48 will leave head 24, allowing spring 23 to project the plunger, closing the contact. The wire 27 will of course be supported so that it may move back and forth with the tubular member 26. It will be observed that all the switch parts are en-

tirely enclosed within the door frame, thus preventing the accumulation of dirt or other foreign matter on the contact surfaces. Should dirt accumulate however on the contact surfaces, the pivoting action described previously will insure engagement of the contacts on at least a portion thereof. Relative radial movement between the contact surfaces 17 and 41 will also be permitted because of the clearance space 25 existing between the plunger 22 and the fastener 11. Should it be desired to repair or replace the switch, it is merely necessary to remove the screw 11 from the hinge and withdraw the switch through the apertures in the nut, frame and hinge. Since the ordinary hinge will be provided with a plurality of attaching screws, the replacement of the switch may thus be effected without in any way disturbing the mounting of the door on the frame.

Figure 4 illustrates a second embodiment of the invention which is similar in principle to that of Figures 1-3, but wherein the plunger spring 49 is enclosed within a tubular member 51 of conductive material which is secured as an extension to the reduced end 52 of fastener 53. In this embodiment, the fastener is provided with an axial bore 54 extending entirely therethrough, this bore being of substantially the same diameter as the plunger 55, so that the plunger is slidably mounted therein. The tubular member 51, which is in effect an extension of the fastener and which acts as a spring housing and as a contact for the switch, is provided with a plurality of inwardly extending tabs 56 which secure the end 51 of the spring 49 against axial movement. The opposite end 58 of the spring is of reduced diameter, and engages a reduced portion 59 of the plunger 55, the shoulder 61 on the plunger preventing movement of this end of the spring. The spring is preferably of the tension type so that the plunger will be normally urged outwardly from the head 62 of the fastener. The inner end of the plunger 55 is provided with a further reduced portion 63 to which is fixedly secured a supporting member 64 of nonconductive material, similar to the supporting member 28 of the previous embodiment. Member 64 is preferably provided with oppositely disposed tapered surfaces 65 and 66, a cylindrical portion 67 extending from portion 65 against spring end 58.

The unit is provided with a combined wire connecting element and contact generally indicated at 68, which is analogous to tubular member 26 of the previous embodiment. This element comprises a wire connector section 69 within which the bare end of the wire 71 is inserted and secured, and a socket section 72 having a plurality of axially extending spring fingers 73 which grip the supporting member 64. These spring fingers have inwardly inclined portions 74 which may be initially forced over the flared surface 66 of the supporting member 64, and thereafter engage the flared surface 65 on the opposite side of this supporting member. The engagement of the spring fingers with supporting member 64 is preferably such that relative rotation between these parts is permitted, so that, as in the previous embodiment, the fastener may be driven home without twisting of the wire 71.

When the plunger 55 of the embodiment of Figure 4 is permitted to move into its extended position, the inwardly inclined portions 74 of the fingers 73 will engage the annular end surface 75 of tubular member 51, thus completing a circuit between the wire 71 and the fastener 53. It will

be observed that, as in the previous embodiment, the spring fingers 73 are completely insulated from the plunger 55, and thus from the fastener, except when the contacts are closed. Likewise, as in the previous embodiment, relative lateral movement will be permitted between the spring finger contacts and the surface 75, by virtue of the play 76 existing between the spring fingers and the supporting member 64.

Figure 5 shows a third embodiment of the invention which is generally similar in principle to that of the previous embodiment but wherein the plunger 77 is fabricated of nonconductive material such as plastic, rather than of conductive material. A contact element 78 of conductive material is rotatably secured to the reduced end 79 of plunger 77. Spring 81 normally urges this contact element into engagement with the end 82 of tubular extension member 83, the angular contact surface 84 of element 78 insuring mutual contact of the elements. The wire 85 is secured within the connector portion 86 of contact member 78. It will be observed that in this construction the supporting member, such as member 64 in Figure 4, is eliminated, since the nonconductive nature of the plunger 77 makes the supporting member unnecessary.

Figures 6 to 9 illustrate two more modifications of the invention which are generally similar in principle to the previous modifications, but which are especially adapted for use in two-wire systems which do not use the grounded fastener as part of the circuit. In Figures 6 and 7 the fastener 87 is provided with an extension member 88 of an annular shape which is rotatably secured to the reduced end 89 of the fastener by means of a snap ring 91. This extension member is fabricated of insulative material and has embedded in its walls a pair of conductors 92 and 93 having contact ends 94 and 95 respectively projecting inwardly into the space 96 within the extension member. Space 96 is preferably of noncircular cross-section, and a contact nut 97 secured to the reduced end 98 of the plunger 99 is slidably housed within this space. A compression spring 101 is held between contact nut 97 and a plug 102 at the end of extension 88, this spring normally urging the contact nut into engagement with contacts 94 and 95. The opposite ends of conductors 92 and 93 extend outwardly from extension 88 and are provided with male terminals 103 and 104 respectively, these terminals being adapted to be engaged by a receptacle 105 attached to the end of the two-wire cable 106. The other end of plunger 99 may be provided with an enlarged head 107 movable within a counterbore 108 in the fastener 87. In assembling the unit shown in Figures 6 and 7, the spring 101 and contact unit 97 will be placed within the tubular housing 88, and this housing then mounted on the end of the fastener by means of snap ring 91. The plunger may then be threadably engaged with contact nut 97, the rotation of the nut being prevented because of the noncircular shape of the nut. It will be observed that a driving rotation of fastener 87 will not cause twisting of wire cable 106, since the snap ring 91 permits relative rotation between the fastener and housing 88. In operation, spring 101 will normally urge contact nut 97 into bridging engagement with contacts 94 and 95, plunger 99 being held in projected position, and depression of the plunger will move the contact nut to interrupt this bridging contact.

Figures 8 and 9 illustrate another embodiment of the two-wire type of switch similar in principle to that of Figures 6 and 7, but which utilizes a

metallic switch housing 109 in place of the nonconductive housing 88 of the previous embodiment. The extension 109 is provided on its outer surface with a pair of oppositely disposed elongated recesses 111 and 112, within which are disposed conductors 113 and 114 respectively. These conductors are preferably insulated by dipping them in rubber or coating them with a plastic varnish or the like, and have inwardly extending contact ends 115 and 116 which project through apertures 117 and 118 respectively in the extension 109. The contact ends 115 and 116 are adapted to be bridged by a U-shaped bridging member 119 embedded in a block 121 of insulated material. Block 121 is slidably disposed within housing 109 and is secured to the reduced end 122 of the plunger, in this case by a bayonet slot 123. The block is normally urged toward the contact ends 115 and 116 by spring 124, so that the ends of the bridging member engage the contact ends. A plug 125, held in place by a pin 126, holds spring 124 within member 109. The outer end of conductors 113 and 114 may be provided, as in the previous embodiment, with male terminals 127 and 128 respectively. A plastic or other insulating sleeve 129 may be positioned over housing 109 to further insulate the conductors and to protect the switch housing.

While it will be apparent that the preferred embodiments of the invention herein disclosed are well calculated to fulfill the objects above stated, it will be appreciated that the invention is susceptible to modification, variation and change without departing from the proper scope or fair meaning of the subjoined claims.

What is claimed is:

1. In combination, a rotatably applied fastener having a shank portion, a plunger within said shank portion, the head of said plunger being movable between a position extending outwardly from said shank portion and a position retracted within said shank portion, an electrical contact movable by said plunger during movement of the latter between its said positions, and a second electrical contact engageable by said first contact during said movement, the two contacts being in engagement when the plunger is in one of its said positions and in spaced relation when the plunger is in its other position.

2. In combination, a fastener having a shank portion and a head portion, the head portion being adapted to be engaged by a tool for applying said fastener, a plunger within said fastener, the head of said plunger being movable between an extended position projecting outwardly of said head portion and a retracted position within said shank portion and out of obstructing relation with said tool, and electrical conductor connecting means carried by said plunger, said connecting means being rotatable with respect to the plunger.

3. In combination, a rotatably applied fastener, a plunger within said fastener, the head of said plunger being movable between a position extending from said fastener and a position retracted within said fastener, electrical contact means actuatable by said plunger during its movement between said positions, and electric conductor connecting means carried by said plunger, said connecting means being rotatable with respect to said plunger.

4. In combination, a rotatable fastener, a plunger within said fastener, the head of said plunger being movable between a position projecting from said fastener and a position retract-

ed within said fastener, electrical contact means actuatable by said plunger into closed position when the plunger moves into its extended position, and resilient means urging the fastener into its extended position.

5. In combination, a rotatable fastener having a shank portion and a head portion adapted to be engaged by a rotating tool, a plunger within said fastener, the head of said plunger being movable between a position extending from said head portion and a portion retracted within said shank position, resilient means for urging said plunger toward its extended position, electrical contact means adapted to be actuated by said plunger, and electrical conductor connecting means carried by said plunger, said connecting means being rotatably mounted with respect to said plunger, whereby the fastener may be rotated without rotating said connecting means.

6. In combination, a rotatably applied fastener, a plunger movable within said fastener, an electrical contact movable by said plunger, and a second electrical contact engageable by said first contact during said movement, said contacts being in engagement when the plunger is in one position and in spaced relation when the plunger is away from said position.

7. In combination, a rotatably applied fastener, an actuating element movable within said fastener, an electrical contact actuatable by said element during its movement, said contact being engageable with said fastener when the element is in one position, and electrical conductor connecting means supported by said fastener, said connecting means being mounted for rotational movement with respect to the fastener.

8. In combination, a fastener, a plunger movable within said fastener, electrical contact means actuatable by said plunger during its movement, said contact means being engageable with an end surface of said fastener in one position of the plunger, resilient means for urging the plunger into said position, and electrical conductor connecting means supported by said plunger, said connecting means being mounted for rotational movement with respect to said plunger.

9. In combination, a fastener, a plunger movable within said fastener, resilient means urging said plunger toward one end of said fastener, electrical contact means carried by said plunger and insulated therefrom, second electrical contact means engageable with said first contact means when said plunger is moved toward said one end of the fastener, and electrical conductor connecting means connected to said first contact means, said connecting means being rotatable with respect to said plunger.

10. In combination, a fastener, a plunger movable within said fastener, resilient means for urging said plunger toward one end of said fastener, an insulating member carried by one end of said plunger, electrical contact means rotatably mounted on said insulating member, second electrical contact means engageable by said first contact means when the plunger is moved toward said one end of the fastener, and electrical conductor connecting means connected to said first contact means, whereby said connecting means is also rotatable with respect to said insulating member.

11. The combination according to claim 10, said first contact means being supported for limited pivotal movement with respect to said insulating member, whereby said first and second

contact means may be mutually engaged at only a portion of their respective surfaces.

5. In combination, a fastener, a plunger movable within said fastener, resilient means for urging the plunger toward one end of the fastener, a tubular member mounted on said plunger and having a contact portion conductively engageable with said fastener when the plunger is urged toward said one end of the fastener, an electrical conductor connecting portion on said tubular member, and means for supporting said tubular member for rotational movement with respect to said plunger.

15. In combination, a fastener, a plunger movably mounted within said fastener, resilient means disposed within said fastener and urging said plunger toward one end of the fastener, an insulating member secured to one end of the plunger, a tubular member supported for rotational and limited pivotal movement on said insulating member, and a contact portion on said tubular member and engageable with the other end of said fastener when the plunger is urged toward said one end of the fastener.

20. In combination, an externally threaded fastener, an axial bore within said fastener and having a shoulder therein, a plunger within said fastener, resilient means disposed within said bore and engageable with said shoulder and one end of the plunger to urge the plunger into a position projecting from one end of said fastener, an insulating member secured to the other end of said plunger, an electrically conductive member rotatably mounted on said insulating member and having a contact portion conductively engageable with the other end of said fastener when the plunger is in said projected position, and electrical conductor connecting means on said conductive member.

25. In combination according to claim 14, said fastener being further provided with a tool-receiving recess, said plunger being movable to a retracted position within said axial bore by the application of a tool to said recess.

30. In combination, a fastener having an extension thereon, a plunger movable within said fastener, resilient means within said extension for urging said plunger toward one end of said fastener, electrical contact means carried by said plunger and conductively engageable with said extension when the plunger is moved toward said one end of the fastener, and electrical conductor connecting means connected to said contact means.

35. In combination, a fastener having an extension thereon, a plunger movable within said fastener, resilient means within said extension for urging the plunger toward one end of said fastener, an insulating member secured to one end of said plunger, and electrical contact means comprising a plurality of fingers mounted on said insulating member and engageable with said extension when the plunger is moved toward said one end of the fastener, said fingers being supported for rotational movement with respect to said insulating member.

40. In combination, a fastener having an extension of conductive material, a plunger of insulative material movable within said fastener, electrical contact means rotatably secured to one end of said plunger and engageable with said extension when the plunger is moved toward one end of said fastener, and means for connecting an electrical conductor to said contact means.

19. In combination, a fastener having a hollow extension rotatably secured thereto, a pair of spaced electrical conductors supported by said extension and having contacts extending into the space within said extension, an actuating element movable within said fastener, an electrical bridging member within said extension and secured to one end of said element, and resilient means for urging said bridging member into engagement with said contacts.

20. In combination, a guide member having an extension rotatably mounted thereon, a pair of electrical conductors supported by said extension, a pair of contacts extending inwardly from said conductors, a plunger movably mounted in said guide member and having a portion extending within said extension, a contact bridging member movably disposed within said extension and secured to said plunger portion, said bridging member being of non-circular shape whereby the bridging member is non-rotatably supported by said extension, and resilient means for urging said bridging member into engagement with said contacts.

21. The combination according to claim 20, said extension being of insulative material, said conductors being embedded in spaced relation within said extension wall.

22. The combination according to claim 20, said extension having axially extending depressions along its peripheral surface, said conductors being disposed within said depressions, and radial apertures in said extension, the ends of said conductors extending through said apertures to form said contacts.

23. The combination according to claim 20, said conductors extending beyond the end of said extension and being adapted to be connected to a two-wire receptacle.

24. A device of the character described comprising in combination, an externally threaded member having a flared and recessed head and adapted to engage an opening in a door hinge, a bore in said member, a plunger longer than

said member and slidably in said bore, a switch housing mounted for rotation at one end of said threaded member, electric conductors carried by said housing and arranged to be contacted by a conductive nut carried at one end of said plunger.

25. In combination, a screw having a longitudinal bore therein, a plunger slidable in said bore, said plunger having a contact nut at one end thereof, a switch housing mounted for rotation on the small end of said screw and arranged to enclose one end of said plunger and said nut, electrical conductors entering said housing and having terminals arranged to be contacted by said nut, means to urge said nut into contacting relation with said terminals and means to limit the movement of said nut away from said terminals.

26. In a device of the character described, including a hinge, a threaded hollow stud having a flared and recessed head and arranged to secure one leaf of said hinge to an automobile frame, a plunger slidable in said hollow stud and having an end arranged to be contacted by the other leaf of said hinge, a contact nut threaded onto the other end of said plunger, a switch housing mounted for rotation on the reduced end of said stud, electric conductors carried by said housing and terminating at one end in elements adapted to be contacted by said nut and terminating at the other end in male terminals extending beyond the end of said housing.

27. The structure of claim 26, including means in said housing for preventing the rotation of said nut.

JOHN W. LILEY.
